(57) **CLAIM**

The ornamental design for a charger for computer, as shown and described.

DESCRIPTION

FIG. 1 is a perspective view of a charger for computer showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof;

FIG. 8 is a reference perspective view thereof showing docking a computer; and,

FIG. 9 is another reference perspective view thereof showing the chargers with computers with legs turned inside.

The broken lines shown in the drawings are included for the purpose of illustrating environmental structure and form no part of the claimed design.
